RADIATOR HOOD CONSTRUCTION

Filed May 29, 1926

Patented Aug. 13, 1929.

1,724,046

UNITED STATES PATENT OFFICE.

PAUL E. SCHLEICHER, OF GARY, INDIANA, ASSIGNEE TO SCHLEICHER, INC., A CORPORATION OF ILLINOIS.

RADIATOR-HOOD CONSTRUCTION.

Application filed May 29, 1926. Serial No. 112,454.

This invention relates to a radiator hood construction and more particularly to a radiator hood support, and is an improvement over the support shown in my Patent No. 5 1,542,101.

Heretofore, it has been necessary to provide cooperating means between the support and bracket on the radiator hood to interlock the two against relative movement. 10 To this end a groove was formed in the support to receive a rib on the end bracket. Sometimes this groove was formed by properly folding and stamping a piece of sheet metal and applying it to the top of the end bracket of the hood and forming a rib on the support. Such a structure was more or 15 less difficult to make, and besides was also expensive.

It is an object of this invention to eliminate such a cooperating groove and rib on the parts, and support the end brackets upon the prongs of the support so that the same will be securely locked against relative movement.

25 The invention comprises the novel structure and combinations hereinafter described and more particularly pointed out and defined in the appended claims.

In the accompanying drawings, which illustrate a preferred embodiment of this invention, and in which similar reference numerals refer to similar features in the different views—

Figure 1 is a broken elevational view of a 30 radiator showing a hood in section secured by my improved support.

Figure 2 is a broken top plan view of the radiator with the cover of the hood and water pan removed.

40 Figure 3 is a sectional view through an end bracket of the hood with a portion of the securing support shown in elevation.

Figure 4 is an enlarged front end elevational view of the support.

45 Figure 5 is an enlarged fragmentary sectional view of an end bracket of the hood showing one of the supports in elevation, illustrating the manner of assembling.

In the drawings, there is shown, a bank 50 of radiator coils 1, which is partially covered by a hood. The hood comprises a rear plate 2 to which end brackets 3 are secured. The end brackets are held together from spreading apart by a tie rod or strip 4, which has lateral ends 5 that are interlocked

with such brackets, as shown in Figures 2 and 3.

Each end bracket is provided with suitable slots or apertures 6 for receiving the prongs 7 on the upright end 8 of the support 9, which is adapted to be clamped to the top of the radiator by a suitable U-shaped clamp 10. The clamps 10 consist of U-shaped members which straddle the connections 1^a between the coils and flat strips 11 extending over the supports 9 and secured to the ends of the U-shaped members.

It will be noted that the end brackets 3 are merely thin plain flat plates i. e., without grooves or the like, and the attaching supports 9 are plain angular members with strengthening ribs 9^a. It will also be noted that the prongs 7 incline or slant downwardly, and that the upper and lower surfaces thereof are substantially parallel. Consequently when the hood is in position upon the radiator and engaged by the prongs 7, it will be effectively interlocked therewith. For instance, if a clamp 10 were removed in Figure 1, it would be impossible to slide its support 9 out of engagement with its end bracket 3 on account of the downward slope of the prongs. Consequently if the hood is in position over the radiator, the supports 9 cannot be engaged with the end brackets 3. Therefore, in assembling, it is necessary to slightly raise the ends of the hood, and upwardly tilt the outer portions of the supports, as shown in full lines in Figure 5. Usually one support is attached at a time. 90 When a support has been interlocked with the hood, it is brought down flat upon the radiator and clamped thereto. Of course the radiator hood will move downwardly with the support. If the parts are properly designed the prongs 7 will serve to clamp the rear plate of the hood against the floor.

From the following it will be evident that I have provided a novel radiator hood construction wherein each support member 9 is adapted to be tilted slightly and the associated bracket member 3 is adapted to be raised in order to align the slanting prong 7 on the support with the aperture 6 in the bracket so that these members can be interlocked. The interlocking of these members is accomplished by moving them downwardly to their normal positions. When in their normal positions these parts cannot be disengaged. To disengage them it is necessary 105

to move them vertically until the prong can be moved out of cooperation with the aperture.

I am aware that many changes may be made, and numerous details of construction may be varied through a wide range without departing from the principles of this invention, and I therefore do not propose limiting the patent granted hereon, otherwise than as necessitated by the prior art.

I claim as my invention:

1. The combination with a radiator, of a hood therefor including end members provided with apertures, and a pair of supports for attaching the hood to the radiator, each support comprising a portion clamped to the radiator, and an upright portion having a downwardly sloping prong engaging one of said apertures.
2. The combination with a radiator, of a hood therefor including flat end members having spaced slots, and a support for each end member having a downwardly inclined prong engaging in one of said slots and normally interlocked therein.
3. In combination with a radiator, a hood including a plurality of end members provided with slots, a plurality of support members on said radiator, each of said support members including a projection cooperable with a slot in the associated end member, said projection being alignable with said slot by tilting the support member and by raising the end member, and said aligned parts being interlocked by moving them downwardly to their normal positions whereby the projection is moved into the slot.

4. In combination with a radiator, a hood for said radiator including a plurality of end members each provided with a slot, a support member associated with each end member and adapted to be connected to the radiator, said support member including a laterally extending prong, said prong slanting downwardly and being insertable in the slot in the associated end member only when the prong is tilted upwardly, each of said end members being adapted to be raised so as to permit disconnection of the associated support therefrom.

5. The combination with a radiator, of a hood including flat end members with slots, a support for each end member engageable in one of said slots when said member is in tilted relation to the said support and locked against detachment therefrom when said end member is in normal position relative to said support.

6. The combination with a radiator, of a hood therefor including flat end members provided with slots, and a support for each end member, said supports having downwardly sloping prongs adapted to extend into said slots, each of said prongs serving to prevent the associated bracket from being disengaged therefrom when the support and the bracket are in normal position relative to each other.

In testimony whereof I have hereunto subscribed my name.

PAUL E. SCHLEICHER.
